Primary Examiner—Stacia Cadmus

(57) **CLAIM**

The ornamental design for a vehicle wheel front face, as, shown and described.

DESCRIPTION

FIG. 1 is a perspective view a vehicle wheel front face showing my new design; and,

FIG. 2 is a front view thereof.

The broken line showing of environment is for illustrative purposes only and forms no part of the claimed design.

1 Claim, 2 Drawing Sheets

FIG. 1

FIG. 2
